UNITED STATES PATENT OFFICE.

FRIEDRICH WILHELM MÜLLER, OF BERLIN, GERMANY.

PRESSER-FOOT FOR SEWING-MACHINES.

SPECIFICATION forming part of Letters Patent No. 346,601, dated August 3, 1886.

Application filed January 20, 1886. Serial No. 189,153. (No model.)

To all whom it may concern:

Be it known that I, FRIEDRICH WILHELM MÜLLER, a subject of the King of Prussia, residing at Berlin, in the Kingdom of Prussia, 5 German Empire, have invented new and useful Improvements in Sewing-Machines, of which the following is a specification.

This invention relates to a new manner of fastening the presser-foot of a sewing-machine 10 to the head of the presser-bar, so that the presser-foot may be rapidly and easily removed or replaced.

The invention consists in the elements of construction hereinafter more fully pointed 15 out.

In the accompanying drawings, Figure 1 is a side elevation of a presser-foot and presser-foot bar embodying my invention. Fig. 2 is a front view of the same. Fig. 3 is a cross-section on line αx , Fig. 1. Fig. 4 is a face view, 20 and Fig. 5 a side view, of the presser-foot.

The letter a represents a presser-foot having the usual hook-shaped form, and provided with a notched shank, e . The presser-bar A is surrounded near its lower end by a clasp or 25 head, B , having one fixed jaw, B' .

b is the movable jaw of head B , pivoted thereto by pivot c . The jaw b has a rearward extension, b' , against which the end of a set-

screw, d , is made to bear. This screw is fitted 30 into a corresponding opening in head B .

D is a set-screw for attaching head B to bar A .

To introduce the presser-foot into the head, the jaw b is first opened, and then the shank 35 e is slipped between the jaws. Next the set-screw d is turned up, so that the jaw b enters and bears against the notched part of the shank. To remove the presser-foot, the screw d is turned back, and then the presser-foot 40 falls out of the head.

I claim as my invention—

1. The combination of bar A and head B , having fixed jaw B' , with pivoted jaw b , having rearward extension b' , and with the set- 45 screws d D , substantially as specified.

2. The combination of bar A and head B , having a fixed and a movable jaw, with presser-foot a , having notched shank e , substantially as and for the purpose specified. 50

In testimony whereof I have signed my name to this specification in the presence of two subscribing witnesses.

FRIEDRICH WILHELM MÜLLER.
